UNITED STATES PATENT OFFICE.

NAPOLEAN H. HEBERT, OF FRANKLIN, NEW HAMPSHIRE.

PISTON-RING.

1,144,474.

Specification of Letters Patent. Patented June 29, 1915.

Application filed October 9, 1914. Serial No. 888,968.

To all whom it may concern:

Be it known that I, NAPOLEAN H. HEBERT, a citizen of the United States, residing at Franklin, county of Merrimack, State of New Hampshire, have invented a certain new and useful Improvement in Piston-Rings, of which the following is a specification, reference being had therein to the accompanying drawings.

10 My invention relates to piston rings of the type employed particularly in connection with internal combustion motors and the like and has for its object the production of a leak-proof ring of improved form and construction.

15 Heretofore so far as known to me serious difficulty has been experienced by manufacturers in producing piston rings which are possessed of the proper amount of tension so that they fit closely against the cylinder walls and prevent leakage past the piston without scoring or otherwise unduly injuring the cylinder. I have found that rings which are cut from a cast iron pot which is 20 one common method of making them are sufficiently soft so that they do not score or otherwise injure the cylinders, but are not possessed of the necessary tension or spring to prevent leakage. On the other hand, I 25 have found that individually cast rings which are well known to have a greater spring or tension than the other type of ring and thus prevent leakage are too hard and not uniform but are apt to have hardened areas which do not wear equally with the softer portions of the ring and, therefore, in a short time wear and score the cylinders.

30 One object of my invention, therefore, is to produce a ring which combines the qualities obtained by using the individually cast ring with those obtained by using the other or pot cast type of ring.

35 Another object of my invention is to so construct the ring that it is leak-proof, an individually cast ring being employed to support a plurality of soft rings which break joints with each other, and are so constructed that they automatically wedge themselves together in the position given so 40 that no leakage may occur between them.

45 Another feature of the ring embodying my invention is that when the parts are assembled they form a single ring, and no screws, or the like are required to hold the parts in their proper relation to each other.

50 My invention will be fully understood from the following description when taken in connection with the accompanying drawings and the novel features thereof will be clearly defined and pointed out in the claims at the close of the specification.

55 In the drawings Figure 1 is a plan view of a ring embodying my invention. Fig. 2 is a view in perspective of the same. Fig. 3 is a section on line 3—3 of Fig. 2. Figs. 4 and 6 are sectional details of the parts shown in Fig. 3 before being assembled.

Having reference to the drawings; Figs. 1 and 2 show a leak-proof ring which consists of a supporting ring 11 and a pair of outer rings 12 and 13. The supporting ring 11 is made of spring metal which has the proper amount of tension or spring required to press outwardly against the cylinder walls and prevent the gas from leaking past the piston. This ring is preferably cast individually for I have found that rings of this type have the necessary tension, but it may be produced in any other 60 well known manner for it does not come in contact with the cylinder walls and acts merely as a supporting member for the other rings as will be hereinafter described. The rings 12 and 13, consist of relatively 65 soft metal being preferably pot cast so that they do not score or otherwise injure the cylinder walls.

70 The supporting ring 11 is of annular shape and provided with the usual opening 90 or cut as shown at 14. In the annular outer surface of the ring 11 is a groove 15.

75 The sides of the groove are beveled as shown at 16 so that they converge inwardly to form flanges or projections 17 each having a vertical outer surface and a beveled inner surface 16 as best shown in Fig. 6.

80 The supporting ring 11 hereinabove described carries a pair of outer rings 12 and 13 which are provided with the usual openings 18 and 19. The rings 12 and 13 are of the same size having vertical edges 29 which are adapted to contact so that when placed together the rings form in effect a single outer ring. The opposite sides of each of the 85 rings are beveled as shown at 20 to the same angle as the bevel of the flanges 17 of the supporting ring 11, the rings together being of such size and shape that they fit within the groove 15 of the supporting ring 11 90 with the beveled edges 20 resting against the beveled surfaces or walls 16 of the flanges 95 105 110

17. When the outer rings 12 and 13 are in position on the supporting ring, their combined width is such that when pressed tightly together as when in the cylinder, 5 there is a space 21 between the bottom of the groove 15 in the supporting ring 11 and the inner periphery of the rings 12 and 13. The outward pressure of the supporting ring 11 causes the flanges 17 to clamp the outer rings 10 tightly together by means of the said beveled portions so that there can be no possible leakage between them. I regard this feature of my invention as an important one for I have found that in leak-proof rings as heretofore constructed although a plurality of 15 outer rings have been employed and their openings arranged in staggered relation a leakage has occurred by reason of the fact that for all practical purposes it is impossible to commercially manufacture the ring parts so that when assembled they fit with such nicety that no leakage occurs between them. By my construction, however, the parts adjust themselves so that when under 20 tension they are clamped tightly together. 25

From the above description it will be noted that the supporting ring does not come in contact with the cylinder walls at any point. This is very important for it enables 30 the use of a split or open spring metal supporting ring adapted to hold the outer rings in place with sufficient pressure.

What I claim is:

1. A piston ring consisting of an inner 35 split or open ring of relatively hard spring metal, said ring having peripheral flanges

forming an outer annular groove, said flanges having beveled inner walls, and two contiguously-placed outer rings of relatively soft metal fitting in said groove between said flanges and projecting outward beyond the periphery of the latter, said outer rings each having a beveled face to fit against the beveled walls of said flanges, so that the outward pressure of the inner spring metal ring 45 will tend to press said rings together, thus preventing leakage between them.

2. A piston ring consisting of an inner split or open ring of relatively hard spring metal, said ring having peripheral flanges 50 forming an outer annular groove, said flanges having beveled inner walls, and two contiguously-placed outer split or open rings of relatively soft metal fitting in said groove between said flanges and projecting outward 55 beyond the periphery of the latter, said outer rings each having a beveled face to fit against the beveled walls of said flanges, so that the outward pressure of the inner spring metal ring will tend to press said 60 rings together, thus preventing leakage between them, said outer split or open rings being so arranged as to break joints with each other and also with said inner split or open ring.

In testimony whereof I affix my signature, in presence of two witnesses.

NAPOLEAN H. HEBERT.
